UNITED STATES PATENT OFFICE.

WILBUR C. SHARP, OF CAMARILLO, CALIFORNIA.

APPARATUS FOR AIDING IN THE FORMING AND NAILING OF BOXES.

Application filed October 8, 1924. Serial No. 742,336.

To all whom it may concern:

Be it known that I, WILBUR C. SHARP, a citizen of the United States, residing at Camarillo, in the county of Ventura and 5 State of California, have invented new and useful Improvements in Apparatus for Aiding in the Forming and Nailing of Boxes, of which the following is a specification.

My invention relates to improvements in 10 apparatus for aiding in the forming and nailing of box bodies and more particularly for holding the ends of a box while the bottom is being nailed on the lower edges of the ends and for holding the cleats positioned on the top edges of the ends while the cleats are being secured prior to fastening the top on the body.

This invention is adapted for use in assembling and securing these parts together 20 in the production of what is commonly termed the "Los Angeles lug" but it will be understood that it is equally applicable in the manufacture of any type of box employing the parts with which my invention is 25 adapted for use.

In the assembling and fastening together of the parts of boxes or lugs in box forms, the operators called "hand nailers" become very expert and produce a large number of 30 box bodies in a given time. It has been customary to use very crude means for assisting the operator in his work and it is the primary object of this invention to provide simple and effective means for aiding the 35 operator so that a much larger number of bodies can be produced each day and so that his work is facilitated and made comparatively easier.

In the accompanying drawing forming part 40 of this specification, Fig. 1 is a plan of my invention showing two ends of a box held in position by my invention, to receive the bottom of the box on the lower ends; Fig. 2 is a side elevation of the structure shown in 45 Fig. 1; Fig. 3 is a side elevation showing the box held by my invention in position to receive the cleats on the top edges of the ends, and Fig. 4 is a plan of a detail showing the gripper members in closed position and 50 holding a cleat in position to be nailed.

In Fig. 1 of the drawing the two ends A and B of a box, the parts of which are to be assembled and fastened are shown held by my invention in position to receive the 55 usual bottom not shown. 12 and 13 are a pair of parallel side arms against the inner

faces of which the two ends A and B are adapted to be held tightly positioned by the presser arms 14 and 15. A suitable base or support 16 is provided upon which said side arms are mounted, the arm 12 being depressible outwardly while the arm 13 is held rigidly. Guide pins 17, vertical supports 18 on the base through which the pins slide freely, expansion springs 19 encircling 60 said pins and wing nuts 20 serve to hold the arms 12 in innermost position to support the end member A. The presser arms 14 and 15 carry antifriction rollers 21 on their outer ends which contact against the ends 65 A and B to hold the latter positioned. The inner ends of said presser arms are pivoted by the vertical shafts 22 on the back member 23 of the device near the back ends of the side members 12 and 13 so that the 70 presser arms may be swung forwardly and backwardly until the rollers strike against said back member in the broken line position shown in Fig. 1 and in the full line position 75 shown in Fig. 3.

As soon as a nailer finishes nailing the bottom to the two ends A and B, he withdraws the body portion of the box thus 80 partly formed out of the device and then 85 nails on the two sides of the box, either entirely by hand or by the aid of what is usually termed a "drop." The body of the box is then returned into the device, open side up, with its ends between the side members 12 and 13, the latter acting as a 90 guide and the side member 12 being depressible outwardly to accommodate any unevenness of the box body. In performing this operation the back wall of the box body 95 strikes against the rollers 21 and pushes the presser arms 14 and 15 back out of the way until the rollers impinge against the back 23. The rollers then act as stops for the box body. The sides 12 and 13 and back 23 are 100 of open work construction so that the presser arms and rollers may work freely in assuming their positions. This movement causes the closing of two pairs of cleat grippers C and D into the position shown in broken lines in Fig. 1 and in full lines shown 105 in Fig. 4.

Each pair of grippers consists of two members, one the outer arm 25 which is secured rigidly on the shaft 22 and the other the inner arm 26 which is mounted rigidly 110 on the pin 27, said pin in turn being journaled in the back member 23. Spring termi-

nal pieces 28 and 29 are mounted upon the arms 25 and 26 respectively and are adapted to spread apart when the presser arms 14 and 15 are swung forwardly.

5 Crank arms 30 and 31 of the pair of grippers D, secured rigidly on the members 22 and 27 respectively are connected respectively to the crank arms 31 and 30 of the companion pair of grippers C by the connecting rods 10 32 and 33 so that when the presser arms are swung the grippers operate simultaneously.

When the uncompleted box body is returned open side up between the side members 12 and 13 its innermost side 35 strikes 15 against the rollers 21 and pushes the presser arms 14 and 15 back until the rollers strike against the back member 23. As the box body reaches this position the grippers close upon cleats 36 laid along the upper edges of 20 the ends of the box body and retain them in suitable position while the nailer nails them to the ends in the exact position desired. After thus nailing, the box body can be slid 25 forwardly out of the apparatus. The cleats can be laid along the upper edges of the ends of the box body before or after the grippers close. When in closed position they are spaced apart and permit the cleat to be easily inserted between them. The outermost 30 spring clips depend over the sides of the ends of the box body so as to align the cleats correctly and the innermost spring clips are not as wide so that clearance is provided for them to swing clearly above the box 35 body.

The apparatus may be variously modified within the spirit of my invention, the construction shown being only illustrative of one embodiment.

40 Having described my invention what I claim as new and desire to secure by Letters Patent is:

1. Apparatus for aiding in the forming and nailing of box bodies, comprising, in 45 combination, a support, a pair of side bars on said support spaced apart and against and between which the ends of a box to be formed are adapted to be placed in upright position to receive the bottom of the box 50 while it is being nailed thereto, a pair of presser elements pivoted on said support to swing into two positions, one in which they are adapted to hold the ends outwardly in upright position against said side bars in 55 nailing position and the other in which they assume a releasing position away from said ends and said box body, and grippers movable to open and close by the action of said presser elements, said opening movement being effected by the movement of the presser elements outwardly against said box ends and said closing movement being effected by the releasing movement of said presser ele-

ments, said grippers being positioned and adapted when closed to hold cleats along the 65 upper edges of the ends of the box body after the sides, ends and bottom of the box have been formed in readiness to finally receive the top.

2. Apparatus for aiding in the forming 70 and nailing of box bodies, comprising, in combination, a support, a pair of side bars on said support spaced apart and against which the ends of a box to be formed are adapted to be placed in upright position to receive the bottom of the box while it is being nailed to said ends, a pair of presser elements pivoted on said support to swing into two positions, one in which they are adapted to hold the ends outwardly against 75 said side bars in said nailing position and the other in which they assume a releasing position away from said ends and box body, and spring grippers movable to open and close by the action of said presser elements, 80 said opening movement being effected by the movement of the presser elements outwardly against said box ends and said closing movement being effected by the releasing movement of said presser elements, said grippers 85 being positioned and adapted when closed to movably hold cleats along the exposed edges of the ends adjacent to the opening of the box body after the sides, ends and bottom of the box have been formed in readiness to 90 finally receive the top.

3. Apparatus for aiding in the forming 95 and nailing of box bodies, comprising, in combination, a support, a pair of side members on said support spaced apart and against and between which the ends of a box to be formed are adapted to be placed in upright position to receive the bottom of the box while it is being nailed to said ends, a pair of presser elements pivoted on said 100 support to swing into two positions, one in which they are adapted to hold the ends outwardly against said side members in said nailing position and the other in which they assume a releasing position away from said 105 ends and back of said box body, and spring grippers connected with said presser elements and movable to open and close by the action of said presser elements, said opening movement being effected by the movement of the presser elements outwardly against said box ends and said closing movement being 110 effected by the inward movement of said presser elements acting under the inward movement of the box body against said 115 presser elements, said grippers being positioned and adapted when closed to movably hold cleats along the upper edges of the ends of the box body.
